(57) **CLAIM**

The ornamental design for a high performance bouncing apparatus, as shown and described.

DESCRIPTION

FIG. 1 is a front perspective view of a high performance bouncing apparatus in accordance with the present invention;

FIG. 2 is a front elevational view of the present invention; FIG. 3 is a right side elevational view of the present invention;

FIG. 4 is a top plan view of the present invention;

FIG. 5 is a bottom plan view of the present invention;

FIG. 6 is a back elevational view of the present invention; and,

FIG. 7 is a left side elevational view of the present invention. The broken lines showing the slots and holes on the body of the high performance bouncing apparatus in FIGS. 1-3, 6 and 7 are for illustrative purposes only; and form no part of the claimed design.
